UNITED STATES PATENT OFFICE.

HENRY A. SCHADOWSKY, OF NEW YORK, N. Y., ASSIGNOR TO JOSEPH RECKENDORFER, OF SAME PLACE.

BOX.

SPECIFICATION forming part of Letters Patent No. 239,274, dated March 22, 1881.

Application filed February 21, 1881. (Model.)

To all whom it may concern:

Be it known that I, HENRY A. SCHADOWSKY, of the city, county, and State of New York, have invented certain new and useful 5 Improvements in Boxes, of which the following is a specification:

My invention relates particularly to boxes for holding lead-pencils, but in some respects is applicable to boxes generally. It is directed to obtaining a cheap, convenient, and readily-applied substitute for the ordinary hook-and-eye fastening used to hold the two hinged parts of a pencil-box together, which substitute is applicable to light boxes generally; 10 and it is also directed to improving the construction and appearance as well of the pencil-box itself.

The nature of my invention can best be explained and understood by reference to the 20 accompanying drawings, in which—

Figures 1, 2, 3, and 4 are perspective views of pencil-boxes of various styles embodying my improvements. Fig. 5 is a view of the box represented in Fig. 1 closed, with parts of the box 25 in section, in order to show the fastening device. Fig. 6 is a sectional view, on an enlarged scale, of that part of the box in which the fastening device is seated.

All of the boxes shown in the drawings contain the same fastening device, so that a description of one will answer for all.

The box shown in Figs. 1 and 5 is composed of two parts, A B, hinged at a, the upper part or top, when the box is closed, fitting snugly 35 between the ends b of the lower part. In each end of the top, near its front, is seated the fastening device, which is shown more plainly in Fig. 6. It consists of a block or core of rubber, c, which fits tightly, and is held in a 40 hole or socket, d, in the top, the rubber not extending to the bottom of the hole, but leaving, as shown, a space, e, in order to allow the pin f the requisite play. This pin is of metal, which is forced into or through the rubber 45 until only its rounded head projects therefrom. The rubber is flush with the end of the top, while the head projects slightly beyond the same. In each end b, at the point opposite the rounded head of the pin when the box is 50 closed, is a slight depression or recess, g, which is entered by the head. The rubber constitutes

a spring, which allows the pins to recede when the top is pressed down between the ends b, and then forces them outwardly as soon as they come opposite to the recesses g. In this way 55 I obtain a fastening which, when the box is closed, will hold the parts together tightly enough for all practical purposes, but which will offer no serious resistance to either the opening or the closing of the box. It is, 60 moreover, extremely cheap, simple, and easy of application. It is, of course, manifest that the position of the parts of the fastening can be reversed—that is to say, the rubber and pin device can be put in the ends b and the recesses g in contiguous faces of the part A.

The box shown in Fig. 1 is composed of two thin boards or wooden strips grooved on their contiguous faces, as shown, so that when closed together the half-round grooves in the one will 70 meet the half-round grooves in the other, and thus inclose the pencils placed therein. The grooves, of course, vary in size and section with the size and shape of the pencils they are to receive. The boxes shown in Figs. 1 and 2 75 are designed for cylindrical pencils; those in Figs. 3 and 4 for hexagonal pencils. The hinge a of the box in Fig. 1 is composed of a strip of some strong pliable material, which is glued to the two parts of the box, as shown. The 80 hinges of the boxes shown in Figs. 3 and 4 are of a similar character.

The box in Fig. 1 is of simple form, and is designed principally to illustrate the construction and arrangement of the fastening device. 85 Those shown in Figs. 2, 3, and 4 have an additional feature which is applicable particularly to pencil-boxes. In one or both of the two parts A B of each of these boxes, at the front, is an extra groove, h, which is to be 90 filled by a rib or projection, i, of corresponding shape, fastened to the other part when the box is closed. The ribs or projections have the shape of the pencils for which the boxes are intended. They are, in fact, wooden sticks 95 or sections of sticks of the same external shape as the pencils. They serve to interlock the box, so as to prevent the hinge from being strained in opening the box, and they also furnish a convenient means for applying the fastening device.

In Fig. 3 the stick i is glued in the front

groove of the top A, and has in each end the fastening device, which operates in connection with the recesses *g* in the sides *b* of the lower part, B, as hereinbefore described. 5 In Fig. 4 the stick is divided into three sections, the two end sections being glued in the front groove of the lower part, B, while the middle section is glued in the front groove of top A. The fastening devices are in the 10 ends of the middle section, as shown. This arrangement enables me to dispense with ends, such as *b*, the ends of the pencil-receiving grooves being closed, as shown, by short plugs *j*, having the same shape as the pencils which 15 the box is to receive. When the box is closed the sections interlock and form, in effect, a single stick. A similar arrangement is shown in Fig. 2, where the box is closed at the sides, not by plugs *j*, as in Fig. 4, but by strips *k*, 20 which meet without overlapping. In this box, instead of a hinge such as shown at *a* in the other figures, I employ a sectional stick, *l*, 25 similar to the front sections in Figs. 2 and 4, except that the middle section is longer. The middle section is glued to the top A and the end sections to the lower part, B. They are then put together, end to end, so as to be in line, and are united by pins (indicated by dotted lines) extending axially through the end

sections into the middle section. These pins 30 constitute the pivot on which the two parts A and B turn.

These boxes are particularly adapted for the pencil trade. They are strong, easily made and put together, and cost little, and they are 35 much more presentable in appearance than the ordinary pencil-box now in the market.

Having described my invention, what I claim, and desire to secure by Letters Patent, 40 is—

1. A box composed of two hinged parts, provided in their adjacent overlapping portions, the one with rubber and pin *c f* and the other with recess *g*, said parts being constructed and arranged for operation as shown and de- 45 scribed.

2. The stick or rib *i*, in combination with the two hinged parts of the box and the fastening device *c f g*, said parts being constructed and arranged for operation as shown and 50 described.

In testimony whereof I have hereunto set my hand this 16th day of February, 1881.

HENRY A. SCHADOWSKY.
